UNITED STATES PATENT OFFICE.

FRANK M. SCHAEFER, OF CHICAGO, ILLINOIS, ASSIGNOR, BY DIRECT AND MESNE ASSIGNMENTS, OF ONE-HALF TO C. M. BENTLEY, OF CHICAGO, ILLINOIS, AND ONE-HALF TO SCHAEFER-DE LUDE-WALLACE COMPANY, A CORPORATION OF ILLINOIS.

VEGETABLE-PARING MACHINE.

1,421,837.

Specification of Letters Patent.

Patented July 4, 1922.

Application filed November 5, 1919, Serial No. 335,852. Renewed December 7, 1921. Serial No. 520,692.

To all whom it may concern:

Be it known that I, FRANK M. SCHAEFER, a citizen of the United States, and a resident of the city of Chicago, in the county of Cook and State of Illinois, have invented certain new and useful Improvements in a Vegetable-Paring Machine; and I do hereby declare that the following is a full, clear, and exact description of the same, reference being had to the accompanying drawings, and to the numerals of reference marked thereon, which form a part of this specification.

This invention relates more particularly to an improved type of a vegetable paring machine wherein an abrasive disk is adapted to be rocked by an eccentric as said disk is rotated.

It is an object of this invention to construct a vegetable peeling machine with an abrasive disk adapted to be rocked while being rotated.

It is a further object of the invention to provide a peeling machine with an abrasive disk adapted to be held in an inclined position by an eccentric shaft when the disk is rotated.

Another object of the invention is to construct a vegetable peeler adapted to drive a tilted abrasive disk from below, and further provide a central refuse drain in the bottom of said peeler.

It is also an object of this invention to provide a vegetable peeler with a gear rotated shaft having an abrading disk pivotally mounted thereon, said disk when rotating adapted to be held in a tilted position by an eccentric arm or shaft.

It is an important object of this invention to construct a vegetable paring machine wherein an eccentrically controlled disk is removably and pivotally mounted on a gear rotated driving shaft.

Other and further important objects of this invention will be apparent from the disclosures in the drawings and specification.

The invention (in a preferred form) is illustrated in the drawings and specification and hereinafter more fully described.

On the drawings—

Figure 1 is a front elevation of a vegetable paring machine embodying the principles of this invention.

Figure 2 is an enlarged transverse section taken on line 2—2 of Figure 1.

55

Figure 3 is a sectional view taken on line 3—3 of Figure 2 with parts in elevation.

Figure 4 is an enlarged fragmentary vertical detail section of the operating mechanisms mounted in the lower portion of the vegetable container.

Figure 5 is an enlarged detail section taken on line 5—5 of Figure 4.

Figure 6 is an enlarged vertical detail section taken through the eccentric mechanism.

65

As shown on the drawings—

The reference numeral 1 indicates a receptacle, tank, or casing provided with a conical or funnel-shaped bottom 2. The casing 1 is supported by pipe legs or supports 3 which project upwardly through tubes 4 formed on the outside of the casing. The upper ends of the legs 3 are secured by means of bolts 5 to a top ring 6 engaged on the upper end of the casing. An apertured cover plate or lid 7 is used to close the casing. The lower end of the casing bottom 2 is provided with an outlet or discharge collar or pipe 8 for the discharge of refuse. A receptacle of any kind may be disposed beneath the discharge pipe 8 to receive the refuse as it is discharged from the paring casing. The front of the casing 1 is provided with a large discharge opening which is normally closed by a door 9. A latch mechanism 10 is provided on the door for holding the same in closed position. A chute 11 is secured to the front of the casing 1 below the door to facilitate discharge of the peeled vegetables.

90

The casing 1 is equipped with an abrasive lining made up of a plurality of curved or arc-shaped panels or sections 12 made of an abrasive material. Each abrasive section or panel 12 is provided on its inner surface with a central longitudinal drain groove 13 which extends from the top to the bottom of the section. The abutting sides or edges of each abrasive section 12 are formed with a central longitudinal groove of semicircular shape, so that the grooves of abutting sections will register with one another when the sections are in place to permit retaining rods 14 to be removably engaged therein for removably holding the abrasive sections secured in position around the interior of the

95

100

105

casing. This arrangement permits independent removal of any of the abrasive sections when damaged or worn.

A motor 15 is supported by a hanging bracket 16 secured on the bottom and to one side of the conical base 2. The motor shaft 17 is vertical and projects upwardly through a bearing 18, into the lower portion of the casing 1. A small driving gear or pinion 19 is secured upon the upper end of the motor shaft 17 and meshes with a large gear 20 keyed upon a short vertical stub shaft 21. The stub shaft 21 is rotatably mounted in a tripod or spider 22, the legs of which are rigidly secured to the inner surface of the conical casing bottom 2. The lower end of the stub shaft 21 is spaced above the discharge pipe 8 to permit escape of the refuse from the casing through said discharge pipe. Integrally formed on the upper end of the shaft 21 above the large gear 20 is a diametrically slotted head 23, having seated therein a pin 24, the ends of which project beyond each side of the shaft head 23.

Mounted on the shaft 21 between the tripod 22 and the large gear 20 is a ball bearing 25.

Removably engaged on the upper rounded portion of the shaft head 23 is a rotatable abrading member adapted to be tilted and comprising a hub 26 provided with a rounded pocket or recess in the bottom thereof as indicated by the reference numeral 27. The pin 24 has the ends thereof secured in the hub 26, through the recess 27 of which said pin diametrically projects. The slot 28 provided in the upper end of the shaft head 23 permits the recessed hub to be removably engaged on the shaft head with the pin 24 seated in said slot 28. Rigidly secured by screws or other suitable means to the hub 26 is a large circular plate 29 the margin of which is bent to afford an upwardly directed flange or rim 30. Cemented or otherwise securely fastened upon the base plate 29 is an abrasive sheet or disk 31 the periphery of which engages the flange 30.

Rigidly secured in the upper end of the hub 26 is the lower end of a shaft or arm 32, the upper end of which has integrally formed on one side thereof a flange or head 33 having a conical recess in the top thereof eccentric to the axis of the shaft 32. As clearly shown in Figure 3, a cross-beam or bar 34 is removably mounted diametrically across the upper portion of the container or casing 1. Integrally formed on one end of the bar 34 is a lug or pin 35 which is adapted to engage in an opening provided in the casing wall. Slidably engaged in the opposite end of the bar 34 is a bolt 36 which is adapted to be retracted to permit mounting or removal of said bar. Adjustably threaded through the central portion of the bar 34 is a vertical pivot screw 37 the lower tapered end 65 of which engages in the eccentric recess pro-

vided in the head 33 of the disk shaft. A lock nut 38 is engaged on the upper end of the pivot screw 37.

The operation is as follows:

The machine is adapted to pare or peel 70 vegetables or fruits. When vegetables such as potatoes are to be peeled, the cover 7 is removed and the potatoes are put into the casing through the open top and supported on the abrasive disk 31. The cover 7 is put 75 in place and the motor 15 is then started. Water may be admitted through the opening in the cover 7 by any suitable kind of hose or spray to wash the contents of the machine. The motor rotates the pinion 19 which in 80 turn rotates the large gear 20 and the shaft 21. The shaft pin 24 seated in the shaft head 23 serves to revolve the abrasive disk 31. As the disk mechanism rotates, it is tipped or inclined as shown in Figure 4. The hub 26 85 acts as a rocker, on the upper end of the shaft head 23. Due to the eccentric disk shaft 32 the abrasive disk is rotated in an inclined position.

This rotatable inclined disk serves to 90 throw the potatoes centrifugally against the abrading sections 12, and said disk 31 being of abrading material also acts to cut the skin from the potatoes, and furthermore acts to roll the potatoes from one side of the casing 95 to the other. The potatoes are thus constantly turned or rolled about to present different portions thereof to the abrading surfaces of the machines. The stationary abrading lining and the revolving abrading disk co-act to cut or scrape away the skin of the potatoes, while the water sprayed into the casing thoroughly washes the same. The water and refuse flow from the casing 1 down through the drain grooves 100 13 and out of the casing through the discharge pipe 8 into any suitable receptacle or drain gutter placed beneath the machine.

The rocking and rotating movement of the inclined abrasive disk acts to roll and shift the potatoes in the machine to rapidly peel the potatoes. When the potatoes have been sufficiently cleaned, the door 9 is opened without stopping the machine and the cleaned potatoes are discharged centrifugally 115 through the open door into a receiving receptacle.

Particular attention is directed to the novel construction of the rotatable abrading disk mechanism which, when rotated, is 120 adapted to be inclined by means of the eccentric shaft 32.

I am aware that numerous details of construction may be varied through a wide range without departing from the principles 125 of this invention, and I therefore do not purpose limiting the patent granted otherwise than necessitated by the prior art.

I claim as my invention—

1. A vegetable paring machine compris-

130

- ing a casing, a rotatable abrading disk disposed therein, and eccentric means for tilting said disk while it is being rotated.
2. A vegetable paring machine comprising an abrasively lined casing, and an eccentrically controlled rotatable inclined abrasive disk removably disposed therein.
3. A peeling machine embracing an abrasively lined casing, an abrasive disk mounted therein, means for rotating said disk, and eccentric mechanisms co-acting with the disk to hold the same inclined as it is rotated.
4. A peeling machine comprising an abrasively lined casing, an abrasive disk pivotally mounted therein, means for rotating the disk, a shaft engaged on said disk, and a means supported in said casing and eccentrically engaging said shaft to incline the disk when rotating.
5. A paring machine comprising a casing, an abrasive disk pivotally mounted therein, means for rotating the disk, a shaft engaged with the disk, a projection formed to one side of the upper end of said shaft and having a recess therein, and a pivot pin engaged in said recess eccentrically with respect to said shaft to hold the disk inclined when rotated.
6. A paring machine comprising an abrasively lined casing, a central discharge pipe in the bottom thereof, a tripod mounted in said casing over the discharge pipe, a shaft supported by the tripod, a gear secured thereon, means for rotating said shaft and gear, a pin projecting diametrically through the shaft, a hub engaged on said pin, an abrasive disk mounted on said hub, a bar removably engaged diametrically in the upper portion of said casing, an adjustable
- pivot pin supported thereby, and a shaft 40 supported on said hub and eccentrically engaging said pivot pin to cause tilting of the disk when rotated.
7. A paring machine embracing an abrasively lined casing, a tripod mounted therein, a vertical shaft supported by the tripod, means for rotating the shaft, a pin projecting diametrically through the shaft, an abrasive disk mechanism removably engaged on said shaft and pivotally supported by said pin, a shaft secured on said disk mechanism, means removably engaged in said casing, and a pin projecting through said means and eccentrically engaged in the upper end of said disk shaft to tilt said disk mechanism.
8. The combination with a paring machine casing, of an eccentrically controlled abrasive disk rotatably and pivotally mounted therein.
9. The combination with a paring machine casing, of an abrasive disk rotatably and pivotally mounted therein, means for rotating said disk, and mechanisms for tilting said disk while it is being rotated.
10. The combination with a paring machine casing, of an abrasive disk rotatably and pivotally mounted therein, and eccentric means for holding said disk in an inclined position when rotating.
- In testimony whereof I have hereunto subscribed my name in the presence of two subscribing witnesses.
